BODY AND UNDERFRAME STRUCTURE FOR MINE CARS

Henry Fort Flowers, Findlay, Ohio

Application July 25, 1951, Serial No. 239,826

1 Claim. (Cl. 105—364)

The invention relates to new and useful improvements in a rail car for carrying ore or the like, and more particularly to improvements in the body and underframe structure therefor.

An object of the invention is to provide a body for rail cars which is fabricated from steel plates of relatively light weight, solely by welding so as to provide a body that has a smooth interior free from projecting parts which can cause ore to stick and which act as starting points for corrosion.

A further object of the invention is to provide a car body of the above type wherein the ends are of double plate construction fabricated from a single smooth inside plate, flanged outside plates and reenforcing webs all welded into an end wall unit which in turn is welded to the side plates of the body for maximum efficiency in transferring load from the side plate girders to the underframe of the car body.

Another object of the invention is to provide a car body of the above type having vertical smooth sides with a reenforcing angle section at the top edge of the sides to add strength and rigidity to the sides, said angle section being welded to the inner face of the side wall and shaped so as to permit the material to flow out of an inverted car with less tendency to stick along the sides of the car.

These and further objects will in part be obvious and will in part be hereinafter more fully disclosed.

In the drawings, which show by way of illustration one embodiment of the invention:

Figure 1 is a side elevation of a rail car embodying the improved body and underframe structure;

Figure 2 is a top plan view of the car;

Figure 3 is a sectional view on the line 3, 3 of Figure 1;

Figure 4 is a sectional view on the line 4, 4 of Figure 2;

Figure 5 is a horizontal sectional view on line 5—5 of Figure 6, showing a portion of the center sill at one end of the car and showing in particular the structural features added thereto for supporting the draft gear and taking up the shocks incident thereto;

Figure 6 is a vertical longitudinal sectional view through the portion of the center sill illustrated on the line 6—6 of Figure 5;

Figure 7 is an end view of the center sill construction as shown in Figures 5 and 6;

Figure 8 is a sectional view on the line 8, 8 of Figure 6;

Figure 9 is a sectional view on the line 9, 9 of Figure 6 and

Figure 10 is a sectional view on the line 10, 10 of Figure 6.

The invention has to do with a rail car for carrying ore and the like and more particularly to the body and underframe structure therefor. The body of the car is indicated at 1 in Figure 1 of the drawings and the under-

2

frame structure at 2. The car body and the underframe structure are mounted on conventional railway trucks indicated at 3, 3.

The body consists of a floor plate 4 which is preferably formed of a single plate of relatively light sheet steel. Extending upwardly from the sides of the floor plate 4 are side plates 5, 5 which are likewise of relatively light weight and are welded all along the sides to the floor plate by a welding. The ends of the body each includes a single piece smooth steel plate 7, a rear lower flanged plate 8 and an upper flanged plate 9. This plate 9 is shaped so as to provide a vertical portion and the flange thereof indicated at 10 abuts against the inner plate 7 and is welded thereto. This upper vertical plate 9 is also welded to the upper end of the inner plate. The lower outer plate 8 is flanged at 11 and the flange abuts against the outer face of the inner plate 7 and is welded thereto. There is also a web 12 extending from the inner plate 7 to the outer plate 8 and there is an inserted plate 13 which is welded to the plate 9 and likewise to the plate 8 so as to lie in a plane common to these plates. This forms the end double wall unit. Both the plate 7 and plates constituting the outer wall of the end structure are welded to the side plates. This makes a very rigid structure which is needed in railroad ore service to withstand end forces due to inertia of the load incurred when coupling, accelerating, and braking. A gusset bar 14 is preferably welded onto the floor plate 4 and also to the inner plate 7 and extends across the end of the body. This gives an added reinforcement to the connection between the lower end of the plate 7 and the floor plate 4. It also helps to prevent material from sticking in the corner between this end plate and floor plate.

There is a gusset bar 15 similar to the bar 14 which extends along each side wall and is welded to a side plate and also to the floor plate. This not only reinforces the connection between the side wall and the floor plate but it also prevents the ore from sticking in the corner where these plates are joined.

At the upper edge portion of each side plate is a reinforcement angle member 16. This angle member is L-shaped and the upper leg 17 is shorter than the lower leg 18. This reenforcing member is welded at the ends of the legs to the inner face of the side plate and extends from one end thereof to the other. The long leg of the reinforcement angle extends downwardly in an inclined direction relative to the side wall and this facilitates the flow of the material from the car when inverted in a rotary dumper. This side reenforcing angle 16 strengthens the top edge of the side and thus adds the strength needed to prevent the top edges from bowing in or out.

At intervals along the side walls 5 are tapered side posts 19 (see Figs. 1, 2 and 3). These side posts are preferably pressed from plates into U-shape and are of gradually decreasing cross sectional area from the lower end to the upper end thereof. As shown in the drawings, there are four of these side posts. They are welded to the floor plate 4 and are welded along their vertical edges to the side plates and at their top edges to the angle plate 16. The side posts being of box-like construction and tapered gradually upward to the top of the car helps increase the strength of the side walls of the car body and their connections to the floor plate and prevent damage from shifting of the load.

From the description above given it will be noted that the car body carrying the load includes the floor plate and all structure thereabove. The under frame for the car body includes the floor plate and the structure therebelow. This under frame structure includes a center sill which extends from one end of the car to the other. The

center sill includes side plates of relatively heavier weight. They are indicated at 20, 20. These plates are spaced from each other and they are welded to the floor plate at their upper edges so that the floor plate is really the top plate of the center sill. A bottom plate 21 is welded to the vertical plates 20, 20, and extends lengthwise of the center sill but terminates short of the ends of the sill where the draft structure is mounted.

In order to reenforce the center sill plates 20, 20, flanges 22, 22 are welded to the lower edges of the plates and also for a part of their length to the bottom plate 21. There are bolsters 23, 23 extending laterally from the opposite sides of the sills in the region of the trucks. These bolsters extend all the way to the sides of the floor plate 4. Welded to the bottom plate 21 and also the reenforcing flanges 22 is a body center plate 24 which fits into the standard truck bolster center plate on the standard railroad truck 3. There are, of course, bolsters associated with each truck and a body plate 24 which is supported by each truck.

The bolster 23 is made up of web side plates 25, 25 at each side thereof, and a bottom plate 26. The plates 25, 25 are spaced from each other and the bottom plate 26 is welded to these plates. The plates at their upper edges are welded to the floor plate 4. These plates 25, 25 are also welded to the plates 20 and to the flanges 22. The bolsters are of box section and are gradually decreasing cross section to the outer end where the bottom plate 26 is welded to the floor plate 4.

Intermediate the ends of each bolster is placed a body side bearing 27 which is made up of a bearing plate 28 and a body side bearing filler 29. This bearing plate 28 and the filler 29 are welded to the underside of the plate 26. There are webs 30, 30 which extend from the plate 26 to the floor plate vertically over this body side plate 28. Webs 30, 30 are not only welded to the floor plate, but they extend across the bolster from one side thereof to the other and are welded to the web side plates 25. These body side bearings 27 prevent buckling or crushing under a concentrated side bearing load.

In order to support the floor plate 4 in addition to the bolsters 3 are double web crossbearers 31 (see Fig. 1). There are three of these crossbearers disposed beneath the floor plate between the trucks and at each side of the center beam. Each cross bearer includes web plates 32, 32 which are vertical and spaced from each other. These plates are welded to the center sill at their inner ends and along their upper edges to the floor plate. There is a bottom cover plate 33 which is welded to the bottom edges of the webs. This makes up a box section and decreases in cross sectional area from the sill to the outer edge of the floor plate. At each side of the center sill there are also single web crossbearers which include a web plate 35 which is welded to the center sill and to the bottom plate and extending laterally from this web plate 35 is a bottom plate which is welded thereto. These single web crossbearers are also tapered from the sill to the outer edge of the floor plate. These crossbearers make a very strong supporting structure for the floor plate.

In Figures 5 and 6 is illustrated an all welded draft structure suitable for an ore car. The structure is especially designed to withstand the loading incident to service in long heavy trains to which is added severe draft shocks incurred in coupling cars at the loading, classifying and dumping stations. This draft structure is designed to take any standard railroad coupler, yoke and friction draft gear. The center sill side plates 20, 20 extend from one end of the car to the other. The flanges 22, 22 are welded to the center sill plates 20, 20 and extend from a position over the truck to the forward end of the car body. The center sill bottom plate 21 terminates short of the end of the center sill in order to provide room for the draft gear of the car.

There is a center sill bulk head 36. There is a king pin hole 37 through the center plate 24 and also a king

pin hole 38 through the bottom plate 21. This bulk head 36 is so placed as to give ample clearance for the standard railroad car king pin (not shown). Extending along the inner faces of the center sill plates 20, 20 are gussets 39, 39. There are three of these gussets. The bulk head 36 is welded to the floor plate and also to the bottom plate 21 as shown in Figure 6. At the ends of the gusset plates 39 are stop plates 40, 40. These are welded to the gussets and also to the side plates 20 and the floor plate. The bottom plate terminates at the stop plates and is welded thereto. The three gusset plates 39 and the bottom cover plate 21 terminate at the rear draft stop plates 40 and provide a strong integral rear draft stop structure. The bulk head top gusset and stop plates 40 are also welded to the floor plate and this further strengthens the rear draft stop structure.

The front draft stop is built up by welding steel bars to the center sill plates 20, 20. The front draft stop plates 41 are welded to the center sill plates 20, 20 and to the end of the floor plate 4. There are two front draft gusset plates 42, 42 and a draft key slotted gusset plate 43. These gusset plates are welded to the side plates of the center sill and are also welded to the draft stop plates 41. There are two of these stop plates 41, one at each side 25 of the sill and also gussets at each side of the sill for backing up each side of the stop plate. This makes a very strong support for the front draft stop plates. The center sill side plates 20, 20 and the center sill flanges 22, 22 extend to the very end of the car body. An end striker 30 plate 44 is welded onto the ends of the center sill plates and also the flanges. This end striker plate 44 has a central coupling opening 45 in which the shank of a standard railroad car coupler is introduced. Above the coupler shank opening is a striker bar 46 which is welded to the outer face of the striker plate 44. The striker back-up plate 47 extends from the front draft stop plates 41. This is a heavy plate and serves the important function of transmitting the forces against the striker bar 46 to the center sill side plates 20, 20 and to the floor plate 4. 35 The coupler shank (not shown) rests on a standard removable coupler wear plate 48 which is usually a steel forging. This wear plate 48 rests on a coupler support plate 49 which in turn is supported and welded to the end striker plate 44 and an auxiliary coupler supporting plate 50.

An important feature of this all welded center sill and structure is its simplicity and the accessibility of the welds both in assembly and repair. It may be noted that in repairing welds on the rear draft stop gusset plates 39 50 it may be desirable to cut out a section of the floor plate 4, after which the section of the floor plate may be welded back in place.

From the above it will be noted that a body construction for a mine rail car has been provided which is fabricated from sheet steel plates of relatively light weight 55 solely by welding so as to provide a smooth body which has a smooth interior free from projecting parts which can cause ore to stick and which projecting parts, if present, act as starting points for corrosion. It will be further noted that a car body underframe structure has been provided which is likewise made from steel plates solely by welding wherein the floor plate is strengthened by a center sill, by bolsters extending laterally of the center sill and also by cross bearers likewise extending laterally from the center sill at intervals along the length thereof. It will be further noted that an underframe 60 structure has been provided with an all welded center sill and with strikers and draft attachments of welded design in which a major part of the coupling and draft gear buffering shocks are transmitted directly to the center sill and floor plate.

It is obvious that many changes in the details of construction may be made without departing from the spirit 65 of the invention as set forth in the appended claim.

I claim:

A rail mine car body and underframe structure comprising a substantially horizontal sheet metal floor plate having a smooth unbroken surface extending from end to end and side to side of said body, sheet metal side plates extending the full length of the floor plate and welded to said floor plate at each side edge thereof, sheet metal end plates welded to the floor plate and the side plates and a center sill including spaced side plates disposed below and extending longitudinally of the floor plate from end to end thereof, said plates being welded at their upper edges to the floor plate, a bottom plate joining the side plates of said center sill, bolsters disposed below and extending transversely of the floor plate from side to side thereof, each bolster including spaced plates welded at their upper edges to said floor plate and at their inner ends to the adjacent plate of the center sill and a bottom plate joining the spaced bolster plates and welded thereto.
